UNITED STATES PATENT OFFICE.

JAMES T. HICKEY, OF RARITAN, AND JOHN SCHNEIDER, OF ELIZABETH, NEW JERSEY.

SWITCH.

1,285,172.

Specification of Letters Patent.

Patented Nov. 19, 1918.

Application filed May 26, 1916. Serial No. 89,999.

To all whom it may concern:

Be it known that we, JAMES T. HICKEY and JOHN SCHNEIDER, residing at Raritan and Elizabeth, in the counties of Somerset and Union and State of New Jersey, respectively, have invented certain new and useful Improvements in Switches, of which the following is a specification.

This invention relates to a switch particularly adapted for the control of high tension electric currents and by means of which circuits carrying such currents may be broken in the open air and the ensuing spark harmlessly dissipated.

15 A more detailed object is to provide an improved construction of switch by the means of which the spark producing terminals, or parts, are adapted to give a "throwing off" effect to the spark at the moment 20 of its appearance.

A further object is to provide improved means for making electrical connection with the moving parts of the switch.

25 A further object is to provide improved construction for the horns employed.

A further object is to provide an improved means for clamping the horns and other parts to the insulator members employed.

30 A further object is to provide improved means for controlling the operation of the switch.

Other objects and aims of the invention, more or less specific than those referred to above, will be in part obvious and in part pointed out in the course of the following description of the elements, combinations, arrangements of parts and applications of principles, constituting the invention; and 40 the scope of protection contemplated will be indicated in the appended claims.

In the accompanying drawings which are to be taken as a part of this specification, and in which we have shown a merely preferred form of embodiment of the invention:

Figure 1 is a side elevational view of a switch constructed in accordance with the principles of this invention.

Fig. 2 is a top plan view of a gang of switches constructed in accordance with the principles of this invention.

Fig. 3 is an enlarged detail view of a portion of the stationary contact member and its means of attachment to the insulator.

Fig. 4 is a view similar to that shown in

Fig. 3, but being taken at right angles thereto.

Fig. 5 is a detail transverse sectional view taken upon the plane of line V--V of Fig. 4.

Fig. 6 is an enlarged top plan view of the movable contact member, a portion of the stationary horn being illustrated in transverse section.

Fig. 7 is a top plan view of the clamp 65 employed for fixing the parts of the device to the insulator elements.

Fig. 8 is an enlarged top plan view of the control lever mechanism shown at the lower part of Fig. 1, parts being shown in section 70 to better disclose the construction.

Fig. 9 is a detail sectional view taken upon the plane of line IX--IX of Fig. 8.

Figs. 10 and 11 are enlarged detail views illustrating a modification, Fig. 11 being a 75 section taken upon the plane of line XI--XI of Fig. 10; and

Figs. 12 and 13 are enlarged views illustrating a further modification.

Referring to the drawings, and particularly to the structure shown in Figs. 1 to 9, for a detailed description of the structure illustrated, the reference character L indicates a base plate upon which the switch is mounted, as best seen in Fig. 1.

In cases where a gang of switches are provided, the base plate L constitutes preferably one element of a platform and is duplicated as many times as there are switches in the gang, as will be readily understood from the showing in Fig. 2. Connecting members 1 are arranged to connect the several base members together to complete the platform. The platform may be supported above the ground upon a pole or 95 tower, if desired, for safety.

Since each switch in the gang is identical in its construction and operation, only one will be described in detail. Where gangs are employed, however, they are usually 100 connected to be controlled by a single control lever to be hereinafter described.

Mounted upon the upper surface of the base plate L is a pin insulator G. This may be of any suitable design and it is rigidly secured to the base plate.

A second insulator H is pivotally mounted upon the base plate. This is preferably of the same style as the insulator G, but its lower end is fixed to a shaft 2 which is journaled in bearings 3 upon the base plate.

The shaft 2 is common to all of the

switches in the gang and it is fitted with a crank arm 4 at one point of its length. A rod 5 engages the outer end of the crank arm and extends downwardly to a point adjacent to the ground, its lower end being connected to a hand lever 6 which is pivotally mounted, as at 7, upon the pole or standard. A rack member 8 is provided adjacent the hand lever and a toothed clamp yoke 9 is carried by the hand lever, the teeth of which, as 10, are arranged to engage the teeth of the rack 8. The clamp yoke 9 is provided with a pair of arms 11 which straddle the hand lever, and a clamp bolt 12 extends between the yoke and the hand lever, being fitted with an adjusting nut 13, whereby the yoke may be forcefully drawn toward the hand lever to clamp the rack 8 firmly between the toothed portion of the yoke and the opposing face of the hand lever. The hand lever will be held against all possible movement while the parts described are in tight clamping position.

When it is desired to move the hand lever, the adjusting nut 13 may be loosened so as to disengage the teeth 10 from the teeth of the rack. A short handle 14 is provided upon the adjusting nut to facilitate its operation.

The outer end portion, as 15, of the hand lever is preferably separately formed and detachable. It is preferably hollow at one end and made to telescope over an extension 16 formed upon the body of the hand lever. The portion 15 may be detached at all times except when it is desired to operate the hand lever.

The hand lever, with the rack and associated parts as just described, constitutes a reliable and efficient lock, for the switch, which is proof against any possible accidental operation.

Suitable adjustable stops 17 may be provided upon the rack 8 for engagement by the hand lever to limit movement of the hand lever in either or both directions.

The stationary insulator G is adapted for supporting the stationary contact member and horn of the switch. The construction of the stationary contact and horn, and the means for attaching it to the insulator, are as follows:

A metallic clamp 18, as best seen in Figs. 3, 4 and 7, is provided, said clamp being formed with an upper or platform portion 19 and lower clamp ring portion 20, which portions are connected together by bowed legs 21. The clamp ring portion is adapted to engage within a groove 22 formed at the upper end of the insulator, and both the platform portion and the clamp ring portion are each made of two parts connected together by clamp bolts 23. By tightening the bolts 23, the clamp ring will engage closely within the groove 22.

A lug 24 is formed upon the upper surface of the platform portion 19 and serves as means for attaching the contact member and horn to said platform portion.

The contact member 25 is made of sheet metal bent into inverted U-shape. The lower ends of the legs of the U straddle the lug 24 and are suitably riveted thereto. A filler block 27 is inserted above the lug 24 so as to lend stability to the structure, and a pair of bolts 28 extend through this filler block and serve to fix a pair of rods 29 and 30 in position, said rods extending vertically upwardly from the platform portion 19 and constituting the stationary horn. These rods are bent toward each other above the member 25 and are fixed together, as at 31, so that the rod 29 constitutes a reinforcing means for the rod 30, the rod 30 being continued somewhat above the upper end of the rod 29 and being further bent, as at 32, to constitute a portion of the spark dissipating surface of the horn.

The opposite or movable horn of the switch is mounted upon the upper end of the insulator H to move therewith. A clamp member 18, similar to that already described, is employed as a means for making the connection. This clamp member is provided with a lug 33 projecting upwardly therefrom in the same manner as is the lug 24 from the clamp member upon the stationary insulator. The lug 33, however, is made larger than the lug 24, and carries a pair of contact arms 34 which are fixed to its opposite surfaces. These arms extend forwardly, toward the stationary horn, and the forward end portions are bent toward each other so as to stand in position to effect a rubbing contact with the opposite side surfaces of the stationary horn when the device is in operation. A filler block 35 is arranged between the arms 34 intermediate the length of said arms. Beyond this filler block, however, the arms are not connected to each other and are resilient with respect to each other so as to improve the frictional contact, as will be readily understood.

A pair of horns 36 are carried one by each of the contact arms 34, said horns having portions 37 which are bent beneath the outer end portions of the contact arms so as to engage against the side surfaces of the stationary horn. Beyond the portions 37 the horns 36 are bent abruptly upwardly and are turned outwardly away from each other, as clearly indicated by comparison of Figs. 1 and 6. The upward bend is to such a degree, that, during the operation of the device, when the contact arms 34 are swung upwardly, a portion, as 38, in the length of the horns 36 will still be in contact with the stationary horn after the end portions 39 of the horns 36 have passed beyond the plane of the stationary horn. An upwardly

flaring V-shaped space is thus defined by the three horns at the moment the portion 38 leaves the stationary horn and the spark is produced. The spark is thus immediately 5 dissipated upwardly between these diverging horns.

The wires bearing the electric current to the two horns may be electrically connected with said horns in any approved manner. 10 It is a part of this invention, however, to provide improved means for connecting the wire to the contact arms of the movable horn. One form of such improved means is illustrated in Figs. 1 and 2, and comprises a pair of toggle links 40 and 41 pivotally connected together. The outer end of the link 40 is pivotally connected to the lug 33 on the movable insulator and the outer end of the link 41 is pivotally connected to a stationary member 42. This stationary member may be carried at the upper end of an insulator 43, similar to the insulator G, as illustrated, if desired.

The line wire, as 44, at one side of the switch is attached to the stationary member 42 and from its point of attachment, as in a socket member 45, a flexible portion 46 extends to a socket member 47 movable with the contact arms 34. The toggle links 40 30 and 41 are provided with eyes 48 at spaced points therealong and the flexible portion of the conductor wire is threaded through said eyes so as to be supported at several points in its length.

35 As the movable insulator is moved, the links 40 and 41 are caused to buckle with respect to each other, as shown by the dotted lines in Fig. 1. The slack produced in the flexible portion of the wire is taken care 40 of by this buckling and no undue strain or bend is occasioned at any particular point in the length of the wire.

The modification Figs. 10 and 11 illustrates the wire 46 as being supported at one 45 point only in its length, namely at the point where the toggles 40 and 41 are pivotally connected together. As shown in these figures, the toggles are each made up of a pair of members spaced apart, a spacing 50 sleeve 49 being interposed in position surrounding the pivot pin 50. A double-eye member 51 is mounted upon the sleeve 49, said sleeve being positioned within one of the eyes of said member. The other eye 55 depends from the sleeve and receives the wire 46 therethrough, as clearly illustrated.

This form of construction is preferable to that shown in Fig. 1, in many instances.

In Figs. 12 and 13 a further modified 60 means of supporting the wire 46 is illustrated. In this modification the toggle links 40 and 41 are dispensed with and in their stead a single spring pressed lever 52 is provided. This lever is formed with an eye 53 65 at its outer end through which the wire 46 is

threaded and the tendency of the lever to swing in one direction will maintain the wire suitably supported at all times. This lever may be mounted in any suitable manner adjacent the wire but it is preferably 70 carried upon the lug 33 of the movable insulator H. It is formed with spaced legs 54 straddling said lug and engaging a pivot rod 55 extending through the lug. A suitable coil spring 56 is mounted upon the rod 75 55 and has one of its ends, as 57, engaging the lug and having its other end 58 engaging the lever 52, the spring exerting tendency to force the outer end of the lever upwardly.

80 It should be mentioned that in some cases it may be found desirable to dispense with one or all of the horns 30 and 36, in which case the circuit will be broken immediately the contact arms 34 leave the contact member 25.

Having thus described our invention what we claim as new and desire to secure by Letters Patent is:

1. A switch comprising a stationary 90 member and a movable member, and means for moving the movable member, the stationary member comprising a platform having a lug upstanding therefrom, an inverted U-shaped member formed of sheet-metal, 95 with the lower ends of its legs straddling and fixed to said lug, and a horn fixed to said U-shaped member extending thereabove to coöperate with portions of the movable member to provide spark dissipating means.

2. A switch comprising a stationary member and a movable member, and means for moving the movable member, the stationary member comprising a platform having a 105 lug upstanding therefrom, a member formed of sheet metal bent into inverted U-shape with its legs spaced apart the lower ends of said legs straddling said lug and fixed thereto, the legs of the U being substantially parallel and extending for a distance above the upper end of the lug, a filler block arranged in the space between said legs above said lug, and a horn fixed to said filler block and extending above the upper 110 end of said U shaped member so as to coöperate with portions of the movable member to provide spark dissipating means.

3. A switch comprising a stationary member and a movable member, and means for 120 moving the movable member, the stationary member comprising a platform having a lug upstanding therefrom, a member formed of sheet metal bent into inverted U-shape disposed with its legs spaced apart the 125 lower ends of said legs straddling said lug and being fixed thereto, the legs of the U being substantially parallel and extending for a distance above the upper end of the lug, the movable member comprising a pair 130

of resilient arms movable into and out of position straddling said U-shaped member, and a pair of horns carried one by each of said resilient arms having portions disposed to engage the opposite surfaces of said U-shaped member.

4. A switch comprising a stationary member and a movable member, and means for moving the movable member, the stationary member comprising a platform having a lug upstanding therefrom, a member formed of sheet metal bent into inverted U-shape and being disposed with its legs spaced apart the lower ends of said legs straddling said lug and being fixed thereto, the legs of the U being substantially parallel and extending for a distance above the upper end of the

lug, the movable member comprising a pair of resilient arms movable into and out of position straddling said U-shaped member, 20 a horn carried by said stationary member projecting upwardly therefrom and a pair of horns one carried by each of said resilient arms disposed to straddle the first horn and to coöperate with said first horn to 25 provide spark dissipating means.

In testimony whereof we affix our signatures in the presence of two witnesses.

JAMES T. HICKEY.
JOHN SCHNEIDER.
